186,661

COLORIMETRIC ANALYZER FOR CHEMICAL DETERMINATIONS

Paul Baldwin, Woluwe-Saint-Pierre, and Silvere Couvreur, Uccle, Belgium, assignors to Interindustrie, Brussels, Belgium, a cooperative society of Belgium

Application October 14, 1958, Serial No. 52,971

Term of patent 14 years

(Cl. D16—2)

Fig. 1 is a left side elevational view of a colorimetric analyzer for chemical determinations, showing our new design;

Fig. 2 is a front elevational view thereof;

Fig. 3 is a right side elevational view thereof;

Fig. 4 is a front perspective view thereof;

Fig. 5 is a top plan view thereof;

Fig. 6 is a bottom plan view thereof; and

Fig. 7 is a fragmentary bottom perspective view thereof.

We claim:

The ornamental design for a colorimetric analyzer for chemical determinations, substantially as shown.
